UNITED STATES PATENT OFFICE.

WALTER JOHNSON, OF MIDDLETON, CONNECTICUT.

SWING.

No. 909,906.

Specification of Letters Patent.

Patented Jan. 19, 1909.

Application filed April 27, 1907. Serial No. 370,565.

To all whom it may concern:

Be it known that I, WALTER JOHNSON, a citizen of the United States, residing at Middletown, in the county of Middlesex and 5 State of Connecticut, have invented certain new and useful Improvements in Swings, of which the following is a specification, reference being had therein to the accompanying drawings.

10 My invention relates to new and useful improvements in swings, and has for its object, among other things, to produce a swing that can be readily manipulated and controlled by the party occupying the same, the chair 15 moving in a substantially horizontal line, and which will be simple in design, of few parts so connected that the swing may be folded.

To these, and other ends, my invention 20 consists in the swing having certain details of construction and combinations of parts as will be hereinafter described and more particularly pointed out in the claim.

Referring to the drawings, in which like 25 numerals of reference designate like parts in the several figures; Figure 1 is a side elevation of my improved swing complete and in operative position; Fig. 2 is a similar view in its folded position; Fig. 3 is a front 30 elevation; and Fig. 4 is an enlarged fragmentary view of the upper end of the chair bar.

In the practice of my invention I provide 35 parallel rockers 1—1 which are rigidly connected by the cross bars 2 and the platform bars 3. The uprights 4—4 are secured at their lower ends to the opposite ends of said rockers by the bolts 5 having the thumb nuts 6 thereon and at their upper ends support the rod 7 which is held against endwise 40 movement by the nuts 8. The radius of the arc of the circle forming the bottom edge of the rockers 1—1 is longer than the distance between the said bottom edge and the 45 center of the rod 7. Suspended from the rod 7 are the chair bars 9 which are connected at their lower ends by the rungs 10 and 11. The back of the chair is constructed with the side bars 12—12 which are united 50 by the cross bars 13 having the slats 14 fixed thereto. Pivots connected with the side bars 12 and chair bars 9 are the arm rests 15, and pivots connected with said side bars 12 is the chair bottom 16. In one side 55 of the bars 12 are the notches 17, and adjacent thereto are the swivel pins 18.

When the chair is in its open position the rung 10 enters the notches 17 and the side bars 12 are secured thereto by the swivel pins 18, as shown in Figs. 1 and 3, in which 60 position the chair bottom 16 rests upon the rung 11 and the arm rests 15 are in a substantially horizontal position.

To take down the chair the swivel pins are rotated, releasing the side bars 12 from 65 the rungs 10 and then the side bars 12 are brought to a position parallel with the chair bars 9, as shown in Fig. 2, which is possible by reason of the swivel connection between the side bars and chair bottom, and the arm 70 rests with the side bars and chair bars. Pivots connected with the chair bars 9 are the posts 19 that are joined at their free ends to a chain 20 secured at its upper end to two of the uprights 4, and at the lower 75 end to a foot rod 21.

The swing is operated by the occupant placing his feet against the foot rod 21, and during the backward movement of the chair, pressing against said foot rod, and removing 80 this pressure during the forward movement thereof. The chair swings upon the rod 7 and at the same time the whole frame rocks upon the rockers 1, giving a double motion and a substantially horizontal movement to 85 the chair, thereby eliminating the fainting feeling that comes in a swing hung in the usual manner and rising and falling during its movement.

In Fig. 1 I have shown by broken lines a 90 portion of my swing when the same is in its forward position.

The length of the chain 20 below the posts 19 may be varied by hitching the chain upon the hooks 22 fixed to said chain and allowing 95 a portion thereof to hang loose.

To reduce to a minimum the friction upon the rods 7, and to eliminate as far as possible wear upon the chair bars 9, the bolts 23 are provided, which pass through said chair bars 100 9 and the apertures 24 therein and rest upon the rod 7, as shown in Fig. 4.

The swing is taken down and folded by releasing two of the uprights 4 from the rockers 1, that is, by unscrewing the nuts 6, 105 after which the parts are folded, as shown in Fig. 2, in which condition it is quite compact in form and can be readily transported.

There are many minor changes and alterations that can be made within my invention, 110 aside from those herein suggested, and I would therefore have it understood that I

do not limit myself to the exact construction herein shown and described, but claim all that falls fairly within the spirit and scope of my invention.

Having described my invention, what I claim as new, and desire to secure by Letters Patent, is:—

In a swing, the combination with parallel rockers having the lower edges formed in the arc of a circle; of companion uprights secured at their lower ends to the outer ends of said rockers, and all connected at their upper ends by a rod located at a distance from said rockers less than the radius of

the circle of which the rockers are an arc; 15 a chair suspended from said rod and movable thereon; companion flexible members fixed at one end to the uprights in rear of said chair, and between their ends to a part upon said chair; and a foot rest rod supported at the lower ends of said flexible members.

In testimony whereof I affix my signature in presence of two witnesses:

WALTER JOHNSON.

Witnesses:

GEORGE E. HALL,
FLORENCE H. MURK.
